(57) **CLAIM**

I claim the ornamental design for a phone case, as shown and described.

DESCRIPTION

FIG. 1 is a front, bottom, right perspective view of a phone case showing my new design;

FIG. 2 is a rear, top, left perspective view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a bottom plan view thereof; and,

FIG. 8 is a top plan view thereof.

The broken lines formed by dashes show unclaimed subject matter and form no part of the claimed design.
